ANSWERING APPARATUS FOR COUPLING A RECORDING AND PLAY-BACK SYSTEM WITH A TELEPHONE SET

H. Albert Campbell, Jr., Portland, and Harold R. Burt, Beaverton, Oreg., assignors to KWF Industries, Inc., Portland, Oreg., a corporation of Washington

Filed June 21, 1965, Ser. No. 85,821

Term of patent 14 years

(Cl. D26—14)

FIG. 1 is a top plan view of an answering apparatus for coupling a recording and play-back system with a telephone set, showing our new design;

FIG. 2 is a side elevational view of the upper side in FIG. 1;

FIG. 3 is a side elevational view of the lower side in FIG. 1;

FIG. 4 is a bottom plan view; and

FIG. 5 is an end elevational view, the opposite end having the same appearance.

We claim:

The ornamental design for an answering apparatus for coupling a recording and play-back system with a telephone set, as shown and described.
